UNITED STATES PATENT OFFICE.

JOHN TOM HAMPTON AND JAMES FLETCHER CALVERT, OF ENGLAND, ARKANSAS.

RUPTURE APPLIANCE.

Application filed December 14, 1925. Serial No. 75,365.

This invention aims to provide a simple but effective means whereby a rupture, and particularly a double rupture, may be retained securely, it being possible to adjust 5 the appliance to suit the anatomical peculiarities of the wearer.

It is within the province of the disclosure to improve generally and to enhance the utility of devices of that type to which the 10 invention appertains.

With the above and other objects in view which will appear as the description proceeds, the invention resides in the combination and arrangement of parts and in the 15 details of construction hereinafter described and claimed, it being understood that changes in the precise embodiment of the invention herein disclosed, may be made within the scope of what is claimed, without 20 departing from the spirit of the invention.

In the drawings:—

Figure 1 shows in front elevation, a device constructed in accordance with the invention;

25 Figure 2 is a top plan;

Figure 3 is a rear elevation;

Figure 4 is a fragmental section taken about on the line 4—4 of Figure 3, remote parts being omitted;

30 Figure 5 is a perspective view showing the body of the pad.

In carrying out the invention there is provided a belt 1, which, preferably, is not elastic, the belt being connected at its ends 35 by a buckle 2, of any desired construction, or by any equivalent device. The numeral 3 marks a depending flexible flap which may be shaped readily to the abdomen of the wearer. The flap 3 comprises an inner 40 layer 4 and an outer layer 5. The outer layer 5 is made of some strong material, such as leather, whereas, the inner layer 4 is made of cloth or other material which will afford the wearer no discomfort. The 45 belt 1 extends between the layers 4 and 5 of the flap 3 at their upper ends, and is connected thereto by stitching 6 or otherwise. The flap 3 is divided to form edges 7, located intermediate the lateral edges of the 50 flap, the inner edges of the spaced wings 10 of the flap diverging downwardly as at 8 and extending downwardly, in approximately parallel relation, at as 9, to the lower edge of the flap 3. The lower edges of the 55 wings 10 are curved outwardly and upwardly, as at 11, to cause them to conform to

the body of the wearer, the upper lateral edges 12 of the flap 3 being parallel, or nearly so. The constituent layers 4 and 5 of the flap 3 may be connected by a stitching 60 14 extended transversely of the flap 3, near to the upper end thereof, and below the belt 1, the stitching being extended about the edges 12, 11, 9, 8 and 7. In the wings 10, on opposite sides of the edges 7, there 65 are eyes 15 adapted to receive a draw string 16. The numeral 17 marks a depending tongue, connected at its upper end to the flap 3 and located on the inside of the flap. The tongue 17 covers the draw string 16 70 and prevents it from affording discomfort to the wearer. Straps 18 are connected to the lower inner corners of the wings 10 and are equipped at their upper ends with slide buckles 19 or the like, forming loops 20 receiving connectors 21 adapted to be mounted on studs 22 secured to the flap 3 near to the longitudinal outer edges 12 of the flap and located about midway between the upper 75 and lower ends of the flaps.

Inwardly extending pads 23 are mounted on the inner surfaces of the wings 10 of the flap 3. The pads 23 may be constructed as desired. Preferably, each pad comprises a cup-shaped elastic rubber body 24 located 80 within a flexible covering 25 of leather or other suitable material, the coverings 25 being connected, about their peripheries, by stitching 26 or the like, with both of the layers 4 and 5, to aid in holding the layers 90 together. Within the body 24 of the pad 23 is located a stuffing 27, which may be made of cotton or any other suitable material.

When the belt 1 is placed about the body of the wearer and adjusted properly, and 95 when the elastic retractile straps 18 are connected at 22 within the flap 3, and are extended around the legs of the wearer, the pads 23 will be held securely in place against the ruptures. The device may be 100 adjusted through the instrumentality of the draw string 16, and because the inner edges of wings 10 diverge as at 8, the article will fit snugly and without discomfort on the body of the wearer.

105 What is claimed is:—

In a device of the class described, a belt, a flap depending from the belt and divided to form wings, the upper portions of the inner edges of the wings being straight and 110 parallel, the intermediate portions of said edges diverging and being shorter than the

upper portions, and the lower portions of said edges being straight and parallel and longer than said upper portions and cooperating with the lower edges of the wings to 5 form inner corners therein, the lower portions of said edges and the inner corners being spaced to form a gap of appreciable width, a lacing cord threaded in a plurality of loops into the wings and extended the 10 full length of the upper portions of the inner edges of the wings, leg straps secured to

the wings at said inner corners thereof, detachable connections joining the straps with the wings at points close to the outer edges of the wings and intermediate the upper and lower ends of the wings, and a pad on the inner surface of one wing. 15

In testimony that we claim the foregoing as our own, we have hereto affixed our signatures.

JOHN TOM HAMPTON.
JAMES FLETCHER CALVERT.
